DESIGN FOR A LADY'S SPAT

Rose K. Lindner, New York, N. Y.

Application September 27, 1940, Serial No. 95,437

Term of patent 14 years

To all whom it may concern:

Be it known that I, Rose K. Lindner, a citizen of Hungary and resident of New York city, in the county of New York and State of New York, have invented a new, original, and ornamental Design for a Lady's Spat, of which the following is a specification, reference being had to the accompanying drawing, forming a part thereof.

Fig. 1 is a side elevational view of a lady's spat, showing my new design.

Figs. 2 and 3 are respectively a perspective view and a bottom plan view, the spat being loosely laced in the back.

I claim:

The ornamental design for a lady's spat, as shown and described.

ROSE K. LINDNER.
